UNITED STATES PATENT OFFICE

99,432

DESIGN FOR A CLOCK DIAL

Alice M. Duffy, Los Angeles, Calif.

Application February 18, 1936, Serial No. 61,228

Term of patent 14 years

To all whom it may concern:

Be it known that I, Alice M. Duffy, a citizen of the United States, residing in the city and county of Los Angeles, State of California, have invented a new, original, and ornamental Design for a Clock Dial, of which the following is a specification, reference being had to the annexed drawing forming a part thereof.

In the drawing the figure is a front view of the clock dial showing my new design, the same being of no appreciable thickness.

I claim:

The ornamental design for a clock dial as shown and described.

ALICE M. DUFFY.
